UNITED STATES PATENT OFFICE.

ADOLPHUS Y. ANDREWS, OF PHILADELPHIA, PENNSYLVANIA.

SKIVING-MACHINE.

SPECIFICATION forming part of Letters Patent No. 621,012, dated March 14, 1899.

Application filed September 4, 1897. Serial No. 650,574. (No model.)

To all whom it may concern:

Be it known that I, ADOLPHUS Y. ANDREWS, of the city and county of Philadelphia, State of Pennsylvania, have invented an Improvement 5 in Skiving-Machines, of which the following is a specification.

My invention has reference to leather-skiving machines; and it consists of certain improvements which are fully set forth in the 10 following specification and shown in the accompanying drawings, which form a part thereof.

The object of my invention is to provide a suitable compact form of skiving-machine for 15 reducing the thickness of leather, along the edges of sheets thereof, by abrading or rubbing off the excess in thickness, and this I perform in a specially-constructed apparatus adapted to secure the results in a uniform 20 manner with absolute reliability, quickness, and cleanliness.

In carrying out my invention I provide a suitable frame in which is journaled a cylinder having a transverse groove in which is 25 driven a piece of wood or other soft material, and about such cylinder I wrap an abrading-sheet of sandpaper, emery-cloth, or other suitable material of the like character and secure it thereto by tacks driven into the said wooden 30 portion of the cylinder. This cylinder is preferably well balanced and driven at a high speed, so as to rub upon the under side of the leather, which is guided thereto by a suitable table and held toward the abrading-roller by 35 means of an adjustable guide adapted to be adjusted to or from the roller to any desired degree, so as to control the thickness of the leather at its skived part. The adjustment is such that the guide may be quickly drawn 40 away from the abrading-roller, so as to permit the removal of the skived leather without abrasion, while at the same time it does not derange the adjustment of the said guide when brought toward the cylinder again. 45 Furthermore, in connection with an apparatus of this character I prefer to employ a suction-tube arranged adjacent to the abrading-cylinder, so as to carry off the abraded portions of the leather, the end of the said suction-tube being provided with a hinged or movable portion adapted to be moved under the

action of the adjustable guide, so as to be moved to or from the abrading cylinder or roller simultaneously with the adjustment of the said guide. The adjustable portion of the 55 suction-tube is designed to cause the suction to exert its influence close to the said adjustable guide, which is the principal place where the abrading action occurs.

My invention will be better understood by 60 reference to the accompanying drawings, in which—

Figure 1 is a plan view of a skiving-machine embodying my improvements. Fig. 2 is a sectional elevation of same on line *xx*. Fig. 65 3 is a cross-section on line *zz* of Fig. 2. Fig. 4 is an enlarged view of a portion of Fig. 2; and Fig. 5 is a sectional elevation of one end of the cylinder, showing the means for counter-balancing.

70

A is the frame of my improved machine.

B is a transverse shaft journaled in the frame by bearings *E*.

D is a band-pulley secured to the shaft *B* and by which it is rotated at a high speed 75 under the action of a belt.

C is a cylinder secured to the shaft *B* and provided with a transverse dovetail groove *f*, extending entirely across it and in which is placed a layer of wood *F* of preferably some- 80 what less thickness than the depth of the groove. As this cylinder revolves at a very high speed it is essential that it should be nicely balanced to prevent liability to injury and also to avoid undue wear upon the journals. To accomplish this balancing, I provide each head of the cylinder with a series of apertures *c*, arranged about the shaft *B*, as near the periphery as is consistent with strength. Into these apertures I drive counterweights of lead *R*² and fill the excess of spaces by plugs of wood *R'*, which are held in place by a cap or plate *S*, secured to the heads by screws *T*. In this manner the counterbalancing can be actually accomplished, 85 90 so that the machine rests perfectly true.

G is a sheet of sandpaper or other suitable abrading substance, which is wrapped about the cylinder *C*, with the ends lapping over the wooden piece or plug *F*, to which it is 100 tacked, as at *g*. In this manner the layer of sandpaper is rapidly carried around with the

rotation of the cylinder C and moves in a circular space.

H is an inclined table fitting in groove-guides I at each side of the machine and forming part of the main frame A. This table may be adjusted to or from the cylinder C. The table is located substantially tangential to the cylinder C, so that the material which is fed over said table is delivered to the cylinder in such a manner as to secure an immediate abrading action without bending. A guide J is arranged parallel to the cylinder C and above it adjacent to the table H, so as to receive the leather and hold it toward the revolving cylinder C. The guide J is bolted to a pivoted frame formed of two cast-iron heads K, secured together by bolts T S', the latter acting as a journal for the rod L, leading downward to a treadle M, which is weighted at m, so as to normally pull down the rod L and move the frame about its pivot-point k, and thereby raise or move the guide J away from the cylinder C. By pressing upon the treadle M with the foot the guide J is moved toward the cylinder C, the extent of such movement being controlled by means of the adjusting-screws O, passing through the main frame A and provided with lock-nuts Q. When the rear end of the frame K T S' is elevated under the action of the treadle, it finally comes to rest against the screws O, and thereby limits the downward motion of the guide J. The distance between the guide J and the cylinder C governs the thickness of the skived portion of the leather.

The lower and forward portion of the cylinder C is inclosed in a box P, carried by the main frame, and supported upon the rear part of the box P is the suction-tube N, which partly incloses the rear portion of the cylinder C.

The upper portion of the tube N is provided with a pivot-plate n, hinged at N', the free end of which rests upon the guide J, so as to rise and fall with it. An opening T² is left between the plate n and the guide J, so as to permit the ready passage of air to enable the carrying off of the abrading portions of the leather and prevent the clogging or soiling of the machine. Without this aperture T² the air would have to come in wholly from the sides, which ordinarily is not satisfactory on a large width of leather.

The table H is adapted to be adjusted in its guides and may be retained in any adjusted position by means of the two side clamps R R, which are pressed forward upon the edges of the wood table by means of springs r. In this manner the adjustment of the table is readily and easily made.

The minor details of construction may be modified without departing from the principles of my invention.

What I claim as new, and desire to secure by Letters Patent, is—

1. In a skiving-machine, the combination of a revolving cylinder having a longitudinal

groove or recess on its periphery, a piece of soft material such as wood into which a fastening device may be driven fitting into said groove and having its outer surface slightly below the outer surface of the cylinder, a sheet of abrading material of slightly-greater length than the circumference of the cylinder wrapped tightly about said cylinder and having its two ends directly lapped upon each other over the surface of the soft material and lying substantially parallel to the circumference of the cylinder, and fastening means directly connecting with and supported by the soft material for tightly holding both ends of the sheet of abrading material firmly to the said soft filling in the recessed portion of the cylinder, the construction being such that the outer surface of the abrading material over the recessed portion does not extend above the outer abrading-surface of the cylinder.

2. In a skiving-machine, the combination of a revolving cylinder having a sheet of sandpaper or abrading-cloth wrapped tightly about it, a feed-table for guiding the material to the skiving-cylinder, a guide for holding the material to the cylinder arranged beyond the end of the table, means for adjusting the guide to or from the cylinder consisting of a movable frame pivoted in fixed bearings and carrying the guide, adjustable stops for limiting the oscillation of the frame and guide in one direction, a weighted treadle to normally move the frame away from the adjustable stop, and a connection between the treadle and the pivoted frame.

3. In a skiving-machine, the combination of a revolving cylinder having its surface covered with a sheet of sandpaper or cloth, a feed-table for guiding the material to the skiving-cylinder, a guide for holding the material to the cylinder, means for adjusting the guide to or from the cylinder consisting of a rocking frame pivoted in fixed bearings carrying the guide at one end, adjustable stops for limiting the oscillation of the frame in one direction, a weighted treadle connecting with the other end of the frame to normally move it away from the adjustable stop and under the action of the foot-pressure to move the pivoted frame against the stop whereby the guide is brought close to but not against the revolving cylinder.

4. In a skiving-machine, the combination of end frames A having bearings E, an abrading-cylinder C journaled therein, a work-supporting table H carried by the frames A and having its end arranged tangentially to the cylinder, a solid frame P secured to the frames A and curved to inclose the lower forward part of the cylinder, a sheet-metal suction tube or case N supported by the frame P and continuing the inclosing of the cylinder on all sides except adjacent to the table and terminating at the top in an adjustable section, and a movable guide adjustable to and from the cylinder supporting the adjustable section

of the suction-case adjacent to the table and at the exposed part of the cylinder.

5. In a skiving-machine, the combination of a revolving cylinder having its surface covered with an abrading material, an adjustable guide movable to or from the cylinder, a table over which the material is fed arranged substantially tangential to the cylinder, a suction-tube having its open end arranged adjacent to the cylinder on the side opposite to the feed-table and adjustable guide, and a pivoted plate hinged to the upper part of the tube and having its free end connecting with the adjustable guides so as 15 to be movable therewith.

6. In a skiving-machine, the combination of a pivoted cylinder having an abrading-surface, a guide under which the leather to be treated is passed, adjusting devices to adjust 20 the guide to or from the cylinder, and a suction-tube arranged at the rear of the guide and having an adjustable extended portion thereof projecting over the revolving cylinder

and adjacent to the adjustable guide and movable to or from the abrading-surface. 25

7. In a skiving-machine, the combination of a revolving cylinder having an abrading-surface, an adjustable guide movable to or from the cylinder and under which the leather is fed, a frame pivoted in fixed bearings and carrying the guide to hold it firmly at all 30 times parallel to the cylinder, a weighted treadle device acting upon the pivoted frame to normally move the guide away from the cylinder but under the action of the foot to 35 move it toward the cylinder but not in contact therewith, and an adjustable stop device to limit the extent of movement of the guide toward the cylinder and prevent actual contact therewith. 40

In testimony of which invention I hereunto set my hand.

A. Y. ANDREWS.
